UNITED STATES PATENT OFFICE.

DENNIS JOHN FLYNN, OF NEW BRUNSWICK, NEW JERSEY.

REINFORCED-CONCRETE FLOOR CONSTRUCTION.

1,338,567.

Specification of Letters Patent. Patented Apr. 27, 1920.

Application filed October 24, 1919. Serial No. 332,893.

To all whom it may concern:

Be it known that I, DENNIS JOHN FLYNN, a citizen of the United States, and a resident of New Brunswick, in the county of 5 Middlesex and State of New Jersey, have invented a new and Improved Reinforced-Concrete Floor Construction, of which the following is a full, clear, and exact description.

10 The object of the invention is to provide a new and improved reinforced concrete floor construction, reinforced longitudinally and transversely to render the floor exceedingly strong and durable.

15 Another object is to provide the floor with voids thereby making the floor exceedingly light.

Another object is to permit of conveniently and quickly forming the floor without 20 requiring highly skilled labor.

With these and other objects in view, the invention consists of certain novel features of construction as hereinafter shown and described and then specifically pointed out in 25 the claims.

A practical embodiment of the invention is represented in the accompanying drawings forming a part of this specification, in which similar characters of reference indicate corresponding parts in all the views.

Figure 1 is a sectional perspective view of the concrete floor construction as applied;

Fig. 2 is a perspective view of one of the slabs;

Fig. 3 is a similar view of one of the light metallic boxes for providing voids in the floor to save cementitious material and to reduce the weight of the floor;

Fig. 4 is a perspective view of one of the 40 stirrups or connecting members between adjacent boxes;

Fig. 5 is a plan view of the floor construction prior to applying the cementitious filling material; and

Fig. 6 is a longitudinal sectional elevation of the same on the line 6—6 of Fig. 5.

The bottom of the reinforced floor construction is formed of slabs 10 arranged in a horizontal plane and in abutting relation, 50 and the slabs 10 are supported during the formation of the floor by a suitable temporary wood form, which is removed after the floor is finished. Each of the slabs 10 is preferably made of terra cotta, gypsum or other cementitious and fireproof material, 55 and is provided at the top and bottom with

longitudinally extending parallel dovetail grooves 13 and 14. Each of the slabs 10 is preferably about fourteen inches square, but I do not limit myself to this particular shape or size. On each of the slabs 10 is centrally set a light metallic box 15 open at the bottom and provided at the sides with outwardly extending flanges 16 extending across the tongues 11 and resting on the top thereof. The front and back of each box 15 is provided with outwardly and downwardly extending flanges 17 extending into corresponding dovetail grooves 13 and under the adjacent side walls of the corresponding tongues 11, as will be readily understood by reference to Fig. 1. By the arrangement described, the boxes 15 are held centered on the corresponding slabs 10 and are prevented from shifting accidentally in a transverse direction by the flanges 17 engaging the dovetail tongues 11. The sides of each box 15 are provided near the top with openings 18 and through the opposite openings 18 of adjacent boxes 15 extend the 75 ends 20 of a connecting and spacing member 21, preferably in the form of a metallic stirrup having its side members 22 abutting against the adjacent opposite ends of the adjacent boxes 15. The ends 20 are in contact with the under sides of the tops of the adjacent boxes, as plainly indicated in Fig. 6, to reinforce the tops of the said boxes. In making the openings 18, the metal of the ends of the box is pushed inward to form 80 supporting flanges 23 for the ends 20, as indicated in Fig. 6. By the arrangement described the boxes 15 are held against accidental shifting in a longitudinal direction.

In order to reinforce the floor, use is made 85 of transverse reinforcing bars 30 each resting on the bottoms of the stirrups 21 of a transverse row of stirrups, the said reinforcing bars 30 bearing on the stirrups to hold the ends 20 thereof in firm contact with the 100 under sides of the tops of the boxes 15, as previously mentioned. In addition to the transverse reinforcing bars 30 use is made of longitudinally extending reinforcing bars 31 resting on the transverse bars 30 and extending between longitudinal rows of the void boxes 15.

After the boxes 15 are placed in position on the slabs 10 and are connected with each other by the connecting members 21 and the 110 reinforcing bars 30 and 31 have been placed in position as described and shown then a

filling 40 of cementitious material is placed on top of the slabs 10 to a depth to embed the boxes 15, connecting members 21 and reinforcing bars 30 and 31. Additional reinforcing bars 50 may be placed in position between the longitudinal rows of boxes 15 as the filling is placed in position, to give additional strength to the floor.

The cementitious filling 40 is placed to a desired depth on the slabs 10 and is molded around the under sides of the I-beams 60 by suitable molds, and on top of the filling 40 is placed the usual floor construction indicated in Fig. 1, but as this floor construction forms no part of my invention it is not deemed necessary to further describe the same. After the temporary wood form or center work used for supporting the slabs has been removed then the ceiling plaster is applied to the under side of the slabs 10 and is securely held thereon by engaging the dovetail grooves 14 and dovetail tongues 12. It will be noticed that by having the dovetail tongues and grooves on both faces of the slabs suitable keys are formed for the cementitious material 40 and the ceiling plaster.

By the use of the metallic boxes 15 voids are produced in the cementitious filling 40 and hence the floor is rendered exceedingly light and a large amount of filling material is saved. As the boxes are made of metal they increase the strength of the floor.

Having thus described my invention, I claim as new and desire to secure by Letters Patent:—

1. A reinforced concrete floor construction comprising slabs arranged in a plane in abutting relation, void forming metallic boxes set on the said slabs in spaced relation, spacing members in the form of stirrups connecting the upper ends of adjacent boxes with each other and forming reinforcements for the tops of the said boxes, reinforcing members extending between adjacent boxes, and a filling of cementitious material in which the said slabs, boxes, connecting members and reinforcing members are embedded.

2. A reinforced concrete floor construction comprising slabs arranged in a plane, void forming metallic boxes one for each slab set in spaced relation on the said slabs, spacing members in the form of stirrups connecting the upper ends of adjacent boxes with each other and having their bottoms above the slabs, the said spacing members engaging with their ends the under sides of the tops of the said boxes to reinforce the same, reinforcing members resting on the bottoms of the said spacing members, and reinforcing members at a right angle to the said spacing members and extending between adjacent rows of the said void forming boxes, and a filling of a

cementitious material held on the said slabs and embedding the said boxes, spacing members and reinforcing bars.

3. A reinforced concrete floor construction, comprising slabs provided with dovetail tongues and grooves on both faces, the slabs being arranged in a plane in abutting relation, metallic boxes, one for each slab, and each provided with outwardly extending flanges at the bottom, the longitudinal flanges of which extend into corresponding grooves and under corresponding tongues of the slab, and the cross flanges extend across the tongues and rest on top thereof, connecting stirrups connecting the adjacent boxes with each other, reinforcing members between the boxes, and a filling of cementitious material on top of the slabs and embedding the said boxes, stirrups and reinforcing members.

4. A reinforced concrete floor construction, comprising slabs provided with dovetail tongues and grooves on both faces, the slabs being arranged in a plane in abutting relation, metallic boxes one for each slab and each provided with outwardly extending flanges at the bottom, of which the longitudinal flanges extend into corresponding grooves and under corresponding tongues of the slab, and the cross flanges extend across the tongues and rest on top thereof, the sides of the boxes having the cross flanges being provided near the top with openings, stirrups, each having its ends extending through the opposite openings of adjacent boxes, the inner ends of the stirrups bearing against the under sides of the tops of the boxes, transverse reinforcing rods extending between the transverse rows of the boxes and resting on the said stirrups, longitudinal reinforcing rods extending between longitudinal rows of the boxes, and a filling of a cementitious material on the top of the said slabs and filling the exposed portions of the grooves, the said filling embedding the said boxes, stirrups and reinforcing rods.

5. A reinforced concrete floor construction, comprising slabs provided with dovetail tongues and grooves on both faces, the slabs being arranged in a plane in abutting relation, metallic boxes, one for each slab and each provided with outwardly extending flanges at the bottom, of which the longitudinal flanges extend into corresponding grooves and under corresponding tongues of the slab, and the cross flanges extend across the tongues and rest on top thereof, the sides of the boxes having the cross flanges being provided near the top with openings, stirrups each having its ends extending through the opposite openings of adjacent boxes, the inner ends of the stirrups bearing against the under sides of the tops of the boxes, transverse reinforcing

rods extending between the transverse rows of the boxes and resting on the said stirrups, longitudinal reinforcing rods extending between longitudinal rows of the boxes, a filling of a cementitious material on the top of the said slabs and filling the exposed portions of the grooves, the said filling em-

bedding the said boxes, stirrups and reinforcing rods, and a plastered ceiling applied to the under side of the slabs and 10 filling the bottom dovetail grooves of the slabs.

DENNIS JOHN FLYNN.
